ABSORPTION MODULATION

Roscoe H. George and Richard C. Webb, West
Lafayette, Ind., assignors to Radio Corpora-
tion of America, a corporation of Delaware

Application March 16, 1942, Serial No. 434,794

4 Claims. (Cl. 179—171.5)

This invention relates to improvements in modulation systems and is concerned more particularly with a method and means by which the modulation of a high frequency carrier may be more readily carried forward at low power and with relatively small tubes. In its more specific form the invention is particularly directed to the modulation of a carrier frequency of high value, such as that used at the present time in television transmission or the system is particularly adapted for the modulation of a carrier whose frequency is substantially within the general range of that now used in the transmission of television signals. Accordingly, the system herein to be described is particularly adaptable for use in the transmission of television signals where high detail is desired, and where the transmission can be carried forward with a minimum expenditure of power.

According to the prior art various methods have been suggested from time to time for modulating the carrier frequency upon which the intelligence signal is to be transmitted. Among the various systems heretofore suggested and utilized to some extent at least were systems of the type known as the plate modulation systems. These systems have been used considerably for broadcasting and generally require high peak-to-peak modulating voltages, but for television transmissions it has been found that because the modulator tubes operate at relatively low plate efficiency a plate modulation system of usual type is not particularly adaptable for use where a high power output is required.

In other forms of transmission the carrier frequency energy has been modulated by the so-called grid modulation types of transmitters which do not require the same high modulating potentials in the tubes, but here again the efficiency is relatively low.

In still other forms of transmission the so-called absorption type of modulation has been used to some extent and in this type of system some desirable results have been obtained. One form of such a system is described, for instance, in the "Proceedings of the Institute of Radio Engineers" for August, 1938, in an article by W. N. Parker, commencing on page 946, (volume 26, No. 8), in which there is disclosed a method of absorption modulation upon which the present invention is to be considered as an improvement. The present invention has the distinct advantage over what has heretofore been known in the art because it provides a system where the two electron paths which perform the absorp-

tion modulation are connected in parallel and in such a position across the radio frequency lines as to make possible dropping the impedance to a relatively low value. At the same time the present invention always provides that the control electrodes of the modulator tubes are never driven positive, as in the prior art, so that grid current does not tend to flow in the system.

In one broad form the invention consists of 10 providing an amplifier stage, preferably of the class C type, which is suitably coupled in A. C. or D. C. fashion to an electrical transmission line which is electrically equivalent in length to approximately one-quarter wave length of the 15 carrier frequency to be radiated. This line serves essentially according to the present invention as the final plate tank circuit of the final amplifier tube. Then connected cross such transmission line is an impedance matching section which 20 is of the order of one-quarter wave length long and which at its end point has a tapped connection of feeder lines of any suitable or desired length to the antenna proper. At the same end point a further impedance matching 25 section (which can be termed a "modulator line") is connected. This section is approximately one-quarter wave length long and the modulator tubes are connected to the end of this section in a manner which will hereinafter be explained.

It therefore becomes one of the primary objects 30 of the invention to provide a system of absorption or impedance modulation which is relatively simple in its arrangement and construction, and which at the same time shall increase the efficiency of operation over that heretofore known 35 in the prior art systems. At the same time the present invention has as a further object that of providing a transmission system in which a more effective use of side bands in the modulation may be obtained and consequently substantial improvement in the efficiency of transmission.

Other objects and advantages of the present 40 invention are those of increasing the fidelity of operation over the systems known in the prior art so that a more pleasing and a more accurate pictorial representation may be obtained where the invention is applied to television systems.

Other objects and advantages of the invention 45 will become apparent from a consideration of the following specification taken in connection with the accompanying drawing, in which:

Figure 1 is a schematic representation of the transmission line modulation system, and

Figure 2 is a diagrammatic representation of

one form which the invention may assume in its installation.

Referring now to the drawing, and first to Figure 1 thereof, the final amplifier of the system is conventionally represented by the dia-grammatic representation 1. This amplifier is preferably of the push-pull type and operating as a class C radio frequency amplifier. The amplifier 1 is coupled to the line 3 either in A. C. or D. C. fashion. The line 3 is actually a loaded line, and while electrically of the order of one-quarter the wave length of the radiated carrier, it is actually slightly less than that amount. Positive voltage for the push-pull amplifier tubes of the amplifier 1 is supplied from the terminal point 5 so as to be connected to each of the two sections 2 and 4 of the line 3. The line 3, including its component parts 2 and 4, serves essentially as the final plate of the tank circuit of the final amplifier tubes connected within the box 10. Connected at the points 6 and 8 on the branches 2 and 4 of the transmission line 3 are two additional conductors 7 and 9 which are of equal length and also about one-quarter wave length long. These conductors connect at their termination to the conductors 57 and 59 at junction points 14 and 15. The conductors 57 and 59 are arranged to receive energy from the lines 7 and 9 under the control of the modulator tubes conventionally represented within the box 10 and when so arranged this section of the line acts as an impedance inverter section. The line 7 and 9 preferably connects to the transmission line 3 by way of smaller condensers 11 and 12 and at the junction points 14 and 15 there is provided an additional line 18 and 17 which leads to the antenna 21. The section of the conductors 7 and 9 between the transmission line 3 and junction points 14 and 15 is also equal to one-quarter wave length of the transmitted carrier, as is the section of the line 57 and 59 between the junction points 14 and 15 and the modulator 10, although the latter section is somewhat shortened physically because of the capacitive loading of the modulator tubes. The line section 18 and 17 which is connected at the points 14 and 15 to the lines 7 and 9 is not critical as to its length but is made of approximately the same impedance as the line section 7 and 9. This line should also match closely with the input impedance to the antenna 21. In this arrangement it becomes apparent that the lines 2 and 4 should be tuned to resonance with the conductors 7 and 9 removed therefrom. The points 6 and 8 at which condensers 7 and 9 connect to the lines 2 and 4 are established in such a manner that the final amplifier 1 is in resonance both while it is supplying power to the antenna, and at times when a short circuit is placed at the junction points 14 and 15 on the lines 7 and 9.

If now the schematic representation of Figure 1 be further considered, it will be seen that the relationship of the product of the impedance at the sending end (that is, at points 6 and 8, for instance) and the impedance at the receiving end (that is, the ends 14 and 15, for instance) of the transmission lines 7 and 9 shall be $Z_s \cdot Z_r = Z_L^2$ where Z_s is the sending end impedance, Z_r is the receiving end impedance, and Z_L is the line impedance. Under these circumstances, Z_L would be the impedance of the line 7-9 if the sending end impedance is across the junction points 6 and 8 and the receiving end impedance is across the junction points 14 and 15, or Z_L might represent the impedance of

the line 57-59, in which instance the sending end impedance would be across the junction points 14-15 and the receiving end impedance would be represented by the modulator 10.

Referring now to the schematic representation of the circuit diagram of Figure 2, the output electrodes of the final amplifier or the push-pull arrangement of Figure 1 are indicated by the elements 31 and 31'. These are the plate or anode elements of the final amplifier of the video transmitter, and they are connected to the line type tank circuit 3, as hereinabove explained in connection with Figure 1.

As was also pointed out in connection with Figure 1, the plate supply for the tube plates 31 and 31' is connected at the terminal 5, as was also shown by Figure 1, and is fed to the transmission line sections 2 and 4 through the high frequency choke 32 and the adjustable connection to the transmission line provided by the slider element 33. The choke 32 may be bypassed to ground by the small condenser 32'. The one-quarter wave-length transmission lines of low impedance, designated in Figure 1 by the lines 7 and 9, are similarly shown by Figure 2, as are the blocking condensers 11 and 12 connected to the terminal points 6 and 8. The transmission line section of Figure 1 represented between the points 14 and 15 and the modulator 10 is shown in the same relationship in Figure 2, and this line serves as an impedance inverting line and connects to the modulator tube 35 in a manner hereinafter to be explained.

With the impedance method of modulation, the arrangement herein disclosed is so arranged that the modulator tube 35 reflects a variable impedance which is preferably purely resistive against the antenna feeder junction points 14 and 15, which not only varies in voltage across the feeder directly but further reflects a high impedance back into the junction of the transmission lines 7 and 9 with the tank circuit 3. The feeder lines 7 and 9 between the tank line 3 and points 14 and 15 and lines 18 and 17 between the same points and the antenna 21 should preferably be of the same impedance for a video or television transmitter so as to eliminate any matching section.

In order to obtain the greatest percentage modulation with a given modulator tube, the lines 7 and 9 between the tank line 3 and points 14 and 15 and the lines 57 and 59 between the points 14 and 15 and the modulator tube 35, as well as the lines 18 and 17 between the antenna 21 and the connecting points 14 and 15 must be designed to give the most satisfactory range of impedance change at the junction points 14 and 15.

In the prior art arrangements heretofore referred to, provision was made whereby an even number of modulator tubes might be so arranged that their plates connected to the lines 57 and 59 and their filaments connected to ground. However, the arrangement then provided was such that only half of the radio frequency voltage is impressed across each tube, so that the equivalent mean resistance of the modulator can be substantially reduced by the present invention through the connection of the modulator tube sections directly across the lines 57 and 59 so that the full voltage can be applied to the tube, and current can flow during both half cycles of the impressed wave. Of course, under such circumstances it will be apparent no direct current potential is needed on the plates of the

modulator tubes, and the energy which is to be dissipated in the plate is reduced.

According to the present invention, the modulator tube 35 consists preferably of two triode sections having cathode elements 36 and 37, anode elements 38 and 39 and control electrodes 40 and 41, in which the grid or control electrode sections should preferably be balanced to ground. As shown, the arrangement is so connected that the cathode 36 of the first tube section connects preferably directly across the conductors 59 and 60, and the cathode 37 of the second tube section connects directly across the conductors 57 and 58, and the plate or anode of opposite sections of the tube connects to one of the same feeders or conductors as the opposite cathode section. The control or grid electrodes 40 and 41 are connected to opposite end terminals of a tank circuit 43 comprising the adjustable condenser 44 and the inductance 45, which is center-tapped at the point 46 and the video signals which are supplied at the terminal 48 are fed through the coupling condenser 49 to the junction point 46 on the inductance element 45. The resistor 50 connected between the inductance 45 and ground 51 is provided in order that the two sections of the tube 35 may be made self-biasing. Filament voltage for heating the cathode elements 36 and 37 of the tube sections is provided at the terminal points 52, 52' and 53, 53' by way of the conductors 57, 58 and 59, 60 of the transmission line section preferably housed within shielding tubes.

The arrangement of the tube 35 may preferably be such that the tube sections are formed so there is slightly higher capacitance from the grid to the plate than from the grid to the filament, and because of this, some variances from the usual standard type of tube may be desired, but can readily be provided by a suitable selection of the tube geometry.

In the arrangement shown, the impedance between the grids or control electrodes 40 and 41 of the tube sections of the tube 35 is materially increased by the addition of the resonant circuit 43 including the capacitance 44 and inductance 45, where the condenser 44 is preferably tuned to the carrier frequency and the inductance 45 is tapped at its mid-point 46 for the purpose of introducing the video signals, where the tube sections are so formed that the capacitance from the grid to the plate is greater than from the grid to the filament. This causes the grid voltage to be reversed in such a way as to lower the plate impedance of the modulator tubes, and also permits some current to flow during a portion of the cycle.

The provision of resistor 50 is such as to make the tube sections of the tube 35 self-biasing, as above noted, and the advantage of the arrangement then becomes apparent in that the modulator characteristic becomes extremely linear with respect to grid voltage within a range between 10% and 90% of the maximum possible antenna current without the modulator lines connected. With the introduction of the video signal at the point 48 and the feeding of the video signal through the condenser 49 to the mid-point of the inductance 45, it becomes apparent that the resultant inductive reactance of the inductance 45 to the video signals is essentially zero, and consequently it becomes further apparent that with the arrangement provided each of the tubes may draw a very heavy plate current, and since the tubes draw no grid current, in that the con-

trol electrodes never go positive relative to the cathode, the tube may be of the so-called beam type.

With the apparatus arranged as hereinabove described, the following may be assumed to be one explanation of the manner in which the operation takes place.

The impedance inverting line 57-59 is first assumed to be disconnected from the junction points 14 and 15. In this case, the energy inverting line 7 and 9 is perfectly matched to the tank circuit 3 and the feeder line 18 and 17 to the antenna. Under these circumstances, when the tank circuit 3 is energized, no reflections can occur on the impedance inverting line 7 and 9, and substantially all of the energy from the final amplifier 1 flows into antenna 21 through the tank circuit, the impedance inverting lines 7 and 9 and the feeder lines 18 and 17. If now a short circuit is placed across the junction 14 and 15, the voltage applied to the antenna 21 through the feeder lines 18 and 17 is reduced substantially to zero and no energy flows into the antenna. At the same time, the line 7 and 9, if properly adjusted, reflects a very high impedance to the junction point 6 and 8 and, therefore, does not accept energy from the tank circuit 3.

Suppose now that the impedance inverting lines 57 and 59 are connected to junction point 14 and 15 and the impedance inverting line 7 and 9, and that the modulator 10 is carried to a non-conducting state. Under such conditions, the impedance at the modulating end of the line 57 and 59 will obviously be very high and the line 57 and 59 will reflect a short circuit at junction point 14 and 15 which causes the antenna current to fall approximately to zero value. As the conductivity through the modulator device is increased so that the impedance decreases it is apparent that the resistance or impedance as reflected at the point 14 and 15 will be increased until the modulator reaches a state of maximum conductivity which approachese a short circuit at the modulator end of the line 57 and 59 so that the impedance, when reflected at the point 14 and 15, reaches a maximum, and, therefore, maximum current flows into the antenna through the feeder line 18 and 17.

It therefore becomes evident that the modulator device 10 should be capable of producing a relatively wide linear variation in conductivity. It likewise is important that the modulator should be capable of producing a minimum of resistance across the impedance inverting line 57 and 59 with a maximum of modulating signal energy in the positive direction.

These results are accomplished by the present invention through the use of two separate triode sections of the tube, conventionally represented by 35, with provision made for applying the modulating signal energy to the control electrodes 40 and 41 so that for the maximum signal in the positive direction the control electrodes are carried to the nearest point in the positive direction which they are capable of attaining, so that the tube impedance then becomes a minimum, and, likewise, for a maximum signal in the negative direction impressed at terminal 48 the tube sections reach a cut-off value and the tube impedance reaches a maximum.

While suitable values resistance and the like have been indicated for convenience of reference on the drawing and particularly on Figure 1 thereof, it is of course obvious that these values are given merely for illustrative purposes and are in no way to be considered as limit-

ing for wide variances may be made and used efficiently. Accordingly, many and various modifications may be made in the disclosed system without in any way departing from the spirit or scope of the invention as it is defined in the hereinafter appended claims.

Having now described our invention, what we claim is:

1. A signal transmission system comprising a source of carrier frequency energy, a source of control signals for modulating the said carrier frequency energy, and a signal radiating means, a tank circuit for said carrier frequency energy source including a transmission line connected with the said source, an impedance inverting line 15 having one end connected to receive energy from the said transmission line, a feeder line connecting the said impedance inverting line to the said signal radiating means, a second impedance inverting line connected to the opposite end of the said 20 first impedance inverting line, said second impedance inverting line being adapted to receive energy from the source of control signals, and a modulator means to supply said control signals to said second impedance inverting line, said modulator comprising first and second thermionic tube 25 elements each including at least a cathode, an anode and a control electrode and having the cathode of the first tube element and the anode of the second tube element connected to one side of the said second impedance inverting line, and the cathode of the second tube element and the anode of the first tube element connected to the other side of the second impedance inverting line, and means to supply signals from the source to 30 35

the pair of control electrodes so that for signal variance between minimum and maximum values the impedance directly across the said second impedance inverting line varies between maximum and minimum values.

2. The system claimed in claim 1 comprising, in addition, a tank circuit comprising parallel inductance and capacity elements having its ends connected to the control electrodes of said modulator tubes, and means to supply the control signals to the tank circuit.

3. The system claimed in claim 1 comprising, in addition, a tank circuit comprising parallelly connected inductance and capacity elements connected between the control electrodes of said modulator tubes, and a connection between the control signal source and the mid-point of said inductance element to supply signals to control the modulator tubes so that control signals cause the impedance across the junction of the first impedance inverting line and the feeder to the signal radiating means to vary between minimum and maximum for a like range of variation in the control signal.

4. The system claimed in claim 1 comprising, in addition, an oscillatory circuit including parallelly connected inductance and capacity elements connected to the control electrodes of the said modulator tubes, means to supply signals from the source to the mid-point of the inductance to energize the said control electrodes, and means to apply a self-biasing voltage to each of the said modulator tubes.
